PHOTOTUBE MULTIPLIER

Christian C. Larson, Fort Wayne, Ind., assignor,
by means assignments, to Farnsworth Research
Corporation, a corporation of Indiana

Application November 4, 1943, Serial No. 508,895

8 Claims. (Cl. 250—175)

1

This invention relates to electron-optical devices and particularly to a phototube multiplier for dividing an optical image into any desired pattern.

In a conventional phototube multiplier for dividing an optical image the photoelectric cathode is divided into the desired pattern. In this manner a number of individual electron streams are emitted by the cathode and each is separately multiplied by means of an individual electron multiplier. In such a device the image division is secured by subdividing the cathode in a desired manner. Such devices have not been entirely satisfactory for the reason that the formation of a subdivided cathode is relatively difficult.

Another form of phototube multiplier comprises a solid photoelectric cathode and one or more electron multipliers. Such devices, however, have not been utilized for the division of an optical image according to a predetermined plan. The usual employment of devices of this character has been in modulation systems. The solid photoelectric cathode upon which light is projected serves merely to produce a copious stream of electrons. Where a plurality of electron multipliers are used in conjunction with a solid cathode of this type the multipliers ordinarily are conditioned sequentially for operation to effect separate multiplications of the same electron stream.

It is desirable to have an electron-optical device which is provided with a solid photoelectric cathode and also with means by which an optical image projected onto the solid cathode may be divided according to a predetermined pattern so that representative signals may be produced for a plurality of the image components.

It is an object of the present invention, therefore, to provide a novel electron-optical device, whereby individual signals representative of predetermined portions of an optical image may be produced.

Another object of the invention is to provide a novel method of generating signals, whereby to produce simultaneously a plurality of individual signals each representative of a different predetermined portion of an optical image.

In accordance with the invention there is provided an electron-optical device having an evacuated envelope within which there is disposed a photoelectric cathode. There also is disposed within the envelope a plurality of electron multipliers. Each of the multipliers is provided with a secondary emissive electrode of predetermined

form. These electrodes are disposed in a plan spaced from and facing the cathode and are arranged with respect to one another to form an area substantially similar to the area formed by projecting the cathode surface into the plane of the electrodes.

Apparatus of this character is one means for carrying out the novel method in accordance with the instant invention. This method of contemporaneously producing individual signals representative of different predetermined portions of an optical image comprises the following steps:

An electron image corresponding to the optical image is formed. A division of the electron image into different predetermined portions is effected. The different portions of the electron image then are separately multiplied to produce the desired signals.

For a better understanding of the invention together with other and further objects thereof, reference is had to the following description taken in connection with the accompanying drawing, and its scope will be pointed out in the appended claims.

In the accompanying drawing:

Fig. 1 is a longitudinal sectional view of an electron optical device embodying the invention; and

Fig. 2 is a traverse sectional view taken on line 2—2 of Fig. 1.

Referring now to the drawing, there is disclosed an embodiment of the invention employing an optical system of the reflection type which more particularly is known as the so-called Schmidt optical system. This system comprises a spherically shaped light reflecting member 11. There is formed substantially at the center thereof, an aperture 12. A concave surface 13 on the reflector 11 is conditioned by any well known means for the reflection of light. A lens 14, having a configuration suitable to correct for spherical aberration of the reflector 11, is mounted in spaced relation to the reflector by a plurality of angular members such as the spacing members 15 and 16.

A substantially cylindrical transparent evacuated envelope 17 is supported in a suitable manner so that it extends through the aperture 12 of the reflector 11. Sealed through the lefthand end of the tube envelope 17, as viewed in the drawing, is a metallic rod 18. An opaque metallic backing plate 19 is supported at the inner end of the rod 18 and is provided with a substantially spherical surface configuration. A

photoelectric surface 21 is formed on the convex surface of the backing plate 19 by any suitable process such as deposition by evaporation of a photoelectric material. Such a structure constitutes a photoelectric cathode having a spherical surface facing and substantially parallel to the reflecting surface 13 of the reflector 11. Preferably the cathode is located approximately midway between the reflector 11 and the lens 14. The photoelectric surface of the cathode is continuous over the entire area thereof.

There is mounted in the righthand end of the tube envelope 17, as viewed in the drawing, four multistage electron multipliers. The first stage electrodes, such as 22 and 23, of the respective multipliers, are provided with secondary emissive surfaces facing the photoelectric cathode 21 and are arranged in a plane adjacent to the reflector 11. These first stage electrodes may have any predetermined forms depending upon the pattern into which it is desired to divide the optical image. For the purposes of illustrating the invention, it is assumed that the optical image is to be divided into four equal quadrants.

Fig. 2 illustrates the arrangement of the electrodes 22 and 23 with respect to one another and with respect to the other two first stage multiplier electrodes 24 and 25. It is seen that the first stage multiplier electrodes are electrically distinct and are arranged with respect to one another to form an area which is substantially similar to the projection of the photoelectric cathode 21 into the plane of the electrodes.

The second stage multiplier electrodes, such as 26 and 27, associated respectively with the first stage electrodes 22 and 23, are so formed to provide a guide path for the electrons from the cathode-facing surfaces of the first stage electrodes to the rear or righthand sides of these electrodes, as viewed in Fig. 1. The remainder of the electrodes of the respective multipliers may be the conventional box type structures, such as 28 and 29. Each of the multipliers also is provided with a final stage electrode which may be in the form of a plate, such as 31 or 32. Additionally, each of the multipliers is provided with a collector electrode which may be in the form of a grid structure, such as 33 or 34. Electrical connections to the various multiplier electrodes may be made to the exterior of the tube envelope by means of conductors, such as 35 and 36.

A coil 37 is mounted in a manner to surround the space between the photoelectric cathode 21 and the multiplier first stage electrodes, such as 22 and 23. Connections may be made from the coil to a suitable source of the direct current (not shown) by means of conductors 38. Energization of the coil produces a magnetic field which is employed to focus the electron image produced by the photoelectric cathode 21.

Referring now to the operation of the described embodiment of the invention, assume that light forming the optical image, which it is desired to divide into four equal quadrants, is directed from the left as viewed in Fig. 1. This light is transmitted by the lens 14 and is reflected by the reflecting surface 13 of the member 11. The reflected light is concentrated and directed onto the photoelectric cathode 21.

The optical image projected onto the photoelectric cathode in the manner described, causes the cathode to produce a corresponding electron stream. The electron stream is focused by means of the coil 37 to form an electron image corresponding to the optical image in the plane of

the multiplier first stage electrodes, such as 22 and 23. These electrodes, together with similar electrodes 24 and 25, are maintained, in a well known manner, at suitable positive potentials with respect to the photoelectric cathode 21. The electron image produced by the solid cathode is divided into four equal quadrants by the electrodes 22, 23, 24 and 25. This division of the electron image corresponds substantially to the pattern of the multiplier first stage electrode arrangement.

Consider, for example, that portion of the electron image impinging upon the secondary emissive surface of the first stage electrode 22. The secondary electrons produced by the primary impingement are drawn into the input aperture of the second stage electrode 26 by reason of the maintenance of the second stage electrode at a suitably higher positive potential than the first stage electrode. The connections of the multiplier electrodes to a source of direct current potential have not been shown for the reason that such connections are conventional to maintain each succeeding multiplier electrode at an increasingly more positive potential than its predecessor. The secondary electrons traversing the second stage electrode 26 emerge from the output aperture thereof and are directed sequentially through successive stages of the multiplier in a conventional manner.

The electrons collected by the collector electrode 33 are employed to develop, in a conventional manner, the signal in an output impedance (not shown) connected to the collector electrode.

A similar process of electron multiplication is effected contemporaneously with that described by the other electron multipliers. In each case the electron multiplication is of that portion of the electron image corresponding in a pattern to the shape of the multiplier first stage electrode intercepting the electron image portion. Likewise, the signals developed in the respective output circuits connected to the individual multiplier collector electrodes, are representative of the respective portions of the electron image. It is important to note that the individual signal multiplications are effected simultaneously.

It is apparent from the foregoing description of the illustrative embodiment of the invention, together with the described mode of its operation, that a device of this character is susceptible to employment in numerous ways. Also it is to be noted that it is not essential that an electron-optical device of the character described be used in conjunction with an optical system of the reflection type. It is contemplated to be within the scope of the invention that a translucent photoelectric cathode may be employed. In such a case, the optical image may be projected upon the surface of such a cathode opposite to the photoelectric surface in a manner well known to those skilled in the art. Similarly, it should be noted that it is not essential to the successful operation of a device embodying the invention that the multiplier be arranged in the manner shown. It is considered to be within the skill of those versed in the art to provide an arrangement of a plurality of multistage electron multipliers in substantially any other relationship to the photoelectric cathode so long as the first stage electrodes are disposed in a manner to intercept the electron stream produced by the cathode. Similarly, the configuration of the cathode may be substantially different from that shown so long as the arrangement of the multi-

plier first stage electrodes forms an area which is substantially similar to the projection of the cathode into the plane of the electrodes.

While there has been described what, at present, is considered the preferred embodiment of the invention, it will be obvious to those skilled in the art that various changes and modifications may be made therein without departing from the invention, and it, therefore, is aimed in the appended claims to cover all such changes and modifications as fall within the true spirit and scope of the invention.

What is claimed is:

1. In a phototube multiplier device, an evacuated envelope, a photoelectric cathode disposed in said envelope, and a plurality of electron multipliers mounted in said envelope opposite to said cathode, each of said multipliers having a secondary emissive electrode, said electrodes being disposed in a plane spaced from and facing said cathode and collectively having substantially the same shape as the projection of said cathode into the plane of said electrodes.

2. In a phototube multiplier device, an evacuated envelope, a photoelectric cathode disposed in said envelope, and a plurality of electron multipliers mounted in said envelope opposite to said cathode, each of said multipliers having a sector shaped secondary emissive electrode, said electrodes presenting together a substantially complete circular area in a plane spaced from and facing said cathode.

3. In a phototube multiplier device, a transparent evacuated envelope, a photoelectric cathode disposed in said envelope, and four electron multipliers mounted in said envelope opposite to said cathode, each of said multipliers having a quadrant shaped secondary emissive electrode, said electrodes presenting together a substantially complete circular area in a plane spaced from and facing said cathode.

4. A phototube multiplier device comprising, a reflecting member having an aperture therein, a tube having a transparent evacuated envelope extending through said aperture, a photoelectric cathode disposed in said tube, the surface of said cathode facing and being substantially parallel to the surface of said reflecting member, a plurality of electron multipliers mounted in said tube opposite to said cathode, each of said multipliers having a secondary emissive electrode, said electrodes being disposed in a plane adjacent to said reflecting member and facing said cathode and presenting together an area substantially similar to the projection of said cathode into the plane of said electrodes, and means included with said device for producing a field in the space between said photoelectric cathode and said multiplier electrodes to focus the electron stream emitted by said cathode substantially in the plane of said electrodes.

5. A phototube multiplier device comprising, a concave reflecting member having a centrally disposed aperture therein, a tube having a transparent evacuated envelope extending through said aperture, a convex photoelectric cathode disposed in one end of said tube, the surface of said cathode facing and being substantially parallel to the surface of said reflecting member, a plurality of multistage electron multipliers mounted in said tube opposite to said cathode, each of said multipliers having a flat first stage secondary emissive electrode, said first stage electrodes presenting together a substantially complete circular area in a plane adjacent to said

reflecting member and facing said cathode, and means included with said device for producing a field in the space between said photoelectric cathode and said multiplier first stage electrodes to focus the electron stream emitted by said cathode substantially in the plane of said first stage electrodes.

6. A phototube multiplier device comprising, a concave reflecting member having a centrally disposed aperture therein, a lens disposed in spaced relation to said reflecting member and having a configuration suitable to correct for spherical aberration, a tube having a transparent evacuated envelope extending through said aperture, a convex photoelectric cathode disposed in one end of said tube intermediate of said reflecting member and said lens, the surface of said cathode facing and being substantially parallel to the surface of said reflecting member, four electron multipliers mounted in said tube opposite to said cathode, each of said multipliers having a quadrant-shaped secondary emissive electrode, said electrodes presenting together a substantially complete circular area in a plane adjacent to said reflecting member and facing said cathode, and electromagnetic means included with said device and located externally of said tube for producing a longitudinal field in the space between said photoelectric cathode and said multiplier quadrant-shaped electrodes to focus the electron stream emitted by said cathode substantially in the plane of said electrodes.

7. A phototube multiplier device comprising, a spherically-shaped reflecting member having a centrally disposed aperture therein, a lens disposed in spaced relation to said reflecting member and having a configuration suitable to correct for spherical aberration, a tube having a transparent evacuated envelope extending through said aperture, a spherically-shaped photoelectric cathode disposed in said tube intermediate of said reflecting member and said lens, the surface of said cathode facing and being substantially parallel to the surface of said reflecting member, four multistage electron multipliers mounted in said tube opposite to said cathode, each of said multipliers having a first stage quadrant-shaped secondary emissive electrode, said first stage electrodes presenting together a substantially complete circular area in a plane adjacent to said reflecting member and facing said cathode, and an electromagnetic coil included with said device and located coaxially with said tube for producing a longitudinal field in the space between said photoelectric cathode and said multiplier first stage electrodes to focus the electron stream emitted by said cathode substantially in the plane of said first stage electrodes.

8. A phototube multiplier device comprising, a spherically-shaped reflecting member having a centrally disposed aperture therein, a lens disposed in spaced relation to said reflecting member and having a configuration suitable to correct for spherical aberration, a tube having a transparent evacuated envelope extending through said aperture, a spherically-shaped photoelectric cathode disposed in one end of said tube intermediate of said reflecting member and said lens, the surface of said cathode facing and being substantially parallel to the surface of said reflecting member, four multistage electron multipliers mounted in the other end of said tube opposite to said cathode, each of said multipliers having a first stage quadrant-shaped secondary

emissive electrode, said first stage electrodes being electrically distinct and presenting together a substantially complete circular area in a plane adjacent to said reflecting member and facing said cathode, and an electromagnetic coil surrounding the space between said photoelectric cathode and said multiplier first stage electrodes to focus the electron stream emitted by said cathode substantially in the plane of said first stage electrodes.
